ABSTRACT OF THE DISCLOSURE

The disclosure in this case describes essentially a two-step process of explosively forming bulbous articles, one form of which is illustratively described as spherical. The process begins by explosively swaging a hollow tubular blank to reduce the diameter thereof in at least two spaced-apart locations along the tube length by wrapping each stated location with an explosive and detonating the same. Thereafter, the final article shape is achieved by centering an explosive charge within the tubular workpiece equidistant from the two swaged neck portions and detonating the same to expand the workpiece radially outwardly. The expansion step contains further novelty in that a die cavity is evacuated by surrounding the die with a vacuum chamber. The two basic steps when used successively on the same workpiece permit high diametral expansion to be achieved in articles having length greater than critical length without the occurrence of local thinning or ballooning in the expanded portion. In addition, the swaging step is accomplished without any tooling or items of apparatus being required.

BACKGROUND

The invention disclosed herein is applicable to the fabrication of any article which can be formed by expansion of a generally tubular blank by the application of pressure from within the same. The method disclosed herein avoids ballooning or excessive thinning of metal in localized areas during expansion of the blank by a preliminary step of compressing the blank to reduce the amount of localized expansion occurring during the subsequent expansion step.

One result of the method disclosed herein is that an increase in diameter up to 100 percent greater than the initial starting diameter of the tubular blank may be achieved with nearly uniform wall thickness throughout the final article. Moreover, the method disclosed herein is particularly useful in forming unitary articles of such difficult shapes as spherical tanks or containers characterized by complete absence of joining seams or welds throughout the surface of the final article. In contrast to the foregoing result, conventional methods for expanding tubular blanks into articles of spherical or bulbous form are successful primarily in the case of very small diametral expansion ratios only, the precise value of which depends upon the initial length of the blank considered with the starting and final diameters of the workpiece before and after deformation of the same to produce the finished article. Specifically, the amount which a workpiece of any given metal or alloy in tube or cylindrical form may be successfully expanded by conventional tube forming devices without resulting in rupture of the workpiece materials is partly dependent upon the length of the workpiece over which the expansion occurs. For example, a ten percent increase in diameter of a tubular workpiece of short length may be achieved with relative ease by applying fluid pressure within the workpiece sufficient to force the sides radially outwardly in all directions an equal amount, whereas the same diametral ratio of expansion could not be accomplished by the stated method

2

in a workpiece of relatively great length. In the longer workpiece, application of force from within the tube in an amount sufficient to exceed the yield strength of the material therein will result in ballooning or local thinning of the workpiece at some area along its length, followed by rupture of the workpiece material at the stated area if the application of radially outward force is continued. Between the two stated extremes there lies a particular value of length for any given workpiece size, material, condition and expansion ratio which may be termed the critical length, at which expansion under the stated conditions may occur without rupture, and which if exceeded will result in localized and uncontrollable non-uniform thinning followed by rupture. For example, uniform expansion of a tubular blank of aluminum to a diameter in excess of five percent by conventional means when the critical length is exceeded has been found to result in rupture of the material even with superior uniformly of material composition, thickness and surface smoothness in the blank before the forming operation is begun.

OBJECTS

Accordingly, it is a principal object of the invention in this case to provide improved method and means for forming tubular blanks into articles of bulbous form having larger area at one or more cross-sections therethrough than the stated blank.

It is also an object of this invention to provide improved method for swaging tubular workpieces to form throat sections or the like having reduced diameter and increased wall thickness, by means avoiding application of force to such workpieces by dies or the like.

It is another object in this case to provide method and means for expanding tubular blanks into various shapes by pressure applied outwardly by explosive force from within the tube walls.

It is another object of this invention to provide method and means permitting expansion of tubular blanks to form articles having length greater than critical length and cross-sectional sizes substantially in excess of the cross-sectional size of such blanks.

It is a further object of the invention in this case to provide method and means as set forth in the above objects having improved ease, rapidity and lower cost than known methods of producing bulbous articles.

Other objects and advantages will become apparent upon a close reading of the following detailed description of an illustrative embodiment of the inventive concept, reference being had to accompanying drawings, wherein:

FIGURE 1 shows a cross-sectional view taken along the longitudinal center line of an elongate tubular blank arranged for the application of explosive force thereto as suggested by line 1—1 in FIGURE 2.

FIGURE 2 is an end elevational view of the structure shown in FIGURE 1,

FIGURE 3 shows a workpiece deformed by use of the novel method depicted in FIGURES 1 and 2,

FIGURE 4 is a side elevational view, partly broken away and in cross section to reveal details of the apparatus containing a portion of the workpiece from FIGURE 3 and arranged for a final forming step according to the novel method disclosed herein, and

FIGURE 5 is an isolated end elevational view of a portion of the apparatus shown in FIGURE 4.

Referring to the drawings described above, it may be seen that the inventive concept disclosed herein contemplates and includes a workpiece which is initially of tubular form as shown by tube 10 in FIGURE 1, and is formed by a succession of steps according to the novel methods disclosed herein into an article of desired final shape. Illustratively, the final article may be generally spherical corresponding to the die workface contour

shown in FIGURE 4. The forming process begins with the initial compression step suggested by FIGURES 1 and 2, wherein it may be seen that tubular blank 10 is filled with a force absorbing or crushable filler material 12 such as foamed in-place plastic, rubber or plaster. Alternatively, filler 12 may comprise water, provided that the ends of tube 10 (not shown) are first plugged so that the tube will be completely filled without ullage spaces.

Filler 12 functions to prevent lopsided buckling of tube 10 upon application of explosive force symmetrically about the outer surface thereof, in case of workpiece blanks having relatively thin walls. Localized buckling of workpiece 10 is unlikely where the initial thickness of the tubular blank, designated 14 in FIGURE 1, is substantial such as one-fourth inch with a starting diameter of four inches or less, whereby the workpiece material is sufficiently rigid to absorb and safely distribute the entire compressive force, and filler 12 may be safely omitted.

When filler 12 is used, and is contained within workpiece 10 so as to completely fill the same, the workpiece portion which is sought to be deformed by the novel method suggested in FIGURE 1 is wrapped with a layer or sleeve of resilient force-distributing material 16. Also, sleeve 16 protects the workpiece from burning effects of the explosive, and may comprise a relatively thick sheet of hard rubber or the like. Sleeve 16 is concentric with and in substantially continuous contact with the outer surface of tube 10 throughout the length of the sleeve. Thereafter, one or more layers of explosive in sheet form are wrapped about tube 10 on the radially outer surface of sleeve 16 in the manner suggested by the three layers 18 or explosive shown in FIGURE 1 whereby the explosive and the sleeve are concentric and co-axially related to the longitudinal axis of elongate tube 10. Thereafter, suitable explosive detonating means which may take the form of electrically energized blasting caps 20 are preferably arranged substantially symmetrically about items 10, 16 and 18 as shown more particularly by FIGURE 2.

It will be understood that several different kinds of explosive known to the prior art may be used to generate the explosive force capable of deforming tube 10 in the manner suggested by FIGURE 1, such as an explosive in cord form wound about the blanket 16, and that the amount of explosive used will vary according to the rigidity and thickness of the material comprising tubular blank 10. The purpose of using a plurality of electrically detonated blasting caps 20 symmetrically arranged about the workpiece and suggested by FIGURE 2 is to achieve as nearly as possible the simultaneous detonation of the circularly arranged explosive charge. The force generated by detonation of the explosive applies a substantially continuous compressive load about tubular blank 10 deforming the same and reducing the diameter thereof as suggested by broken lines 22 shown in FIGURE 1 and solid lines 24, 26 and 28 in FIGURE 3. The foregoing reduction in diameter is accompanied by a substantial increase in the wall thickness of tubular blank 10 in that portion which is compressed by explosive force in the manner described above. Moreover, the process thus described and shown by FIGURE 1 may be repeated one or more times at the same location to produce successive reductions of workpiece diameter until a desired final value thereof is achieved. The amount of diameter reduction obtainable with each individual application of force depends upon the initial wall thickness, the initial tube diameter, the workpiece material in the tubular blank 10, and the kind of explosive used, all of which may be determined according to well-known principles in the explosive forming art. In addition, a greater amount of wall thickness increase may be achieved for a given amount of diametral decrease where blank 10 is relatively short and thin walled initially, by restraining both ends of the workpiece against movement as suggested by fixed structural surface 23 bearing against the end of blank 10 as shown in FIGURE 1, it being under-

stood that, where necessary or desirable, both ends of the blank are so restrained to prevent elongation of the workpiece simultaneous with diametral reduction thereof.

The initial step described above in practicing the novel methods disclosed herein may be conveniently termed explosive swaging, and represents certain definite improvements over conventional swaging methods which involve mechanical devices for applying force locally and progressively about a tube to reduce the diameter thereof such as by rotary swaging dies. Thus, the forces which may be applied mechanically are severely limited by the strength of the die materials and other factors, including the need for frequent replacement of such dies due to excessive wear resulting from their use with workpiece materials of high strength steel or the like. The method described above and suggested by FIGURE 1, for example, results in improved accuracy in the surface contour, symmetry and uniformity of workpiece thickness and is extremely versatile with regard to the workpiece materials which may be successfully swaged and the high percent of diametral decrease achievable by the foregoing method. Moreover, the stated advantages are achieved without any tooling being required. Thus, the stated method has been successfully used to effect diametral reductions of 50 percent and higher in workpiece blanks of stainless steel, using three successive detonation steps identical to that suggested in FIGURE 1.

The explosive swaging technique described above has been found extremely useful in the preparation of workpiece tubular blanks to form bulbous shapes such as spheres and the like, wherein swaging is accomplished at spaced-apart locations along an elongate tubular blank 10 illustratively shown by FIGURE 3. In the stated figure, swaging by the method described above at a plurality of locations along workpiece 10 results in reduced workpiece diameters indicated by reference numerals 24, 26 and 28, with intermittent bulbous portions 30 and 32 having the same initial diameter and wall thickness as workpiece 10 before the swaging operations occurred. Portions 30 and 32 are thereafter separated by cutting along a plane centered therebetween as indicated by reference numeral 34 in FIGURE 3, after which either of the individual portions may be used to form an article of desired final shape such as the hollow sphere suggested by FIGURE 4.

Referring to FIGURE 4, workpiece portion 32 having swaged end portions 26 and 28 is placed within a hollow die 40 which may be separately formed in two oppositely corresponding half sections held together by suitable means such as a plurality of elongate bolts 42 and nuts 44. Die 40 has a hollow cavity 46 therein, the cavity walls comprising a workface 48 size and shaped according to the desired final configuration of the article sought to be made from workpiece 32. Cavity 46 has circular openings 50 and 52 at the top and bottom thereof, respectively, sized to receive end portions 26 and 28 and to make substantially continuous surface contact therewith but not necessarily in force-fitting relationship. Die 40 is supported on a substantially planar base plate 54 which provides a stable reference surface for the die and for a vacuum chamber 56 of convenient form such as a cubical or cylindrical shape and which is sized so as to enclose die 40 therewithin and to provide a spacial gap 58 between chamber 56 and die 40.

Chamber 56 is preferably of high strength material such as steel and is provided with a sealing flange 60 which is coextensive with the lower edge of the vacuum chamber and is adapted to overlie a groove 62 in the surface of steel base plate 54 as shown in FIGURE 4. Groove 62 contains a suitably resilient sealing element 64 which may comprise a rubber ring of familiar type and round in cross section but deformable under compression within groove 62 as shown in FIGURE 4. Chamber 56 is further provided with a vacuum line 66 for connection with a pump (not shown) whereby all atmosphere or other gases within chamber 56 may be evacuated

through vacuum line 66. To provide escape means for excess explosive force and water or other filler materials during the explosive forming process, a blasting exit 68 is provided in vacuum chamber 56 and substantially aligned over top portion 26 and opening 50 of die 40 as shown in FIGURE 4. Blasting exit 68 may be substantially circular in shape and a cover member 70 of suitable material, such as hard rubber or plastic having sufficient rigidity to resist the force of the vacuum within chamber 56, is adapted to cover exit 68 in sealing relationship therewith. Restraining means of any appropriate form which may illustratively comprise I beam sections 72 and 74 may be provided in the relationship shown by FIGURE 4 to inhibit or otherwise restrain the amount of movement of cover member 70 under the force of detonation during the explosive forming process.

The explosive forming process may begin by filling workpiece portion 32 with a suitable filler such as water and immersing an explosive charge 78 substantially in the center thereof and appropriately connected for detonation by electrical means in a conventional manner. With workpiece 32 positioned in die 40 as seen in FIGURE 4, chamber 56 is evacuated by connection of vacuum line 66 with a vacuum pump, whereby cavity 46 in die 40 is also simultaneously evacuated along with spacial gap 58 due to pressure communication means interconnecting the same such as passage 80 unless communication between the mentioned areas is already provided by looseness of fit between workpiece portion 26 and opening 50, for example. Thereafter, explosive charge 78 is detonated, resulting in explosive force in the form of one or more shock waves radiating outwardly from charge 78 and causing deformation of workpiece portion 32 outwardly and forcefully into contact with workface 48 of die cavity 46. During the outward deformation of the mid portion of workpiece 32, elongation and resultant thinout of the material in the mid portion is less than it would have been had a straight tube been bulged having the diameter of ends 26 and 28. Local thinning of walls in portions 26 and 28 due to the stated pattern of expansion within die 40 is avoided by the initially heavy wall thickness in both said portions achieved by the swaging step described above in connection with FIGURES 1 and 2. Such avoidance permits articles of greater than critical length (with respect to the amount of diametral expansion) to be formed by the process disclosed herein.

From the description set forth above and the structure shown in the drawings, it will be understood that the inventive method disclosed herein essentially comprises at least two successive deformation steps which include the initial compression of a workpiece blank to increase the wall thickness thereof at desired predetermined locations, followed by expansion of the same workpiece at other locations thereon to achieve a final workpiece shape in the finished article. Moreover, it will be understood that either of the successive steps thus illustratively shown may be separately used to achieve different or other workpiece shapes or used in conjunction with other methods and deformation steps known to the explosive forming art. Thus, the use of vacuum chamber 56 to evacuate cavity 46 in die 40 affords particular advantages in the method described in connection with FIGURE 4, by avoiding the problems associated with sealing of a die cavity such as would be required between end portions 26, 28 and their respective openings 50 and 52 in the absence of vacuum chamber 56. The ease, economy and rapidity of the evacuating method thus recited is a separate and very significant feature of the invention disclosed herein. Conversely, the successive steps of swaging and then expanding tubular workpiece shell blank 10 as discussed above may be advantageously practiced without the use of vacuum chamber 56. In addition, depending on workpiece material characteristics and amount of explosive force required to deform it, filler materials 12 and 76 may be omitted when not required in a given

case, and expansion of blank 32 may conceivably be accomplished by dieless forming in which case die 40 might be eliminated as unnecessary in practicing the broad concept taught herein.

While the particular structural details and method set forth above and in the drawings are fully capable of attaining the objects and providing the advantages herein stated, the structure and method thus disclosed are merely illustrative and could be varied or modified to produce the same result or portions of the process separately used without departing from the scope of the inventive concept as defined in the appended claims.

We claim:

1. A method of forming a throat section in a rigid elongate cylindrical blank having a substantially constant initial cross-sectional area along some portion of its length, said method comprising:

initially preplacing firmly rigid but crushable filler material comprising low density plastic material within said blank, placing a protective sleeve of flexible force-transmitting material circumferentially around said blank and in contact with the outer surface thereof, arranging explosive material in the form of a plurality of layers in sheet form wrapped over said protective sleeve and in substantial axial alignment therewith, and detonating said explosive sheet material to apply substantially uniform circumferentially distributed radially inwardly directed force to said blank.

2. A method of forming a bulbous article from an elongate hollow tubular blank having a mid-portion of larger diameter than each of the two end portions adjoining said mid-portion, said method comprising:

supporting said blank by restraining said two ends in a support, placing an explosive charge with said blank, filling said blank with shock-wave transmitting material, placing said blank and said support in a surrounding vacuum chamber, evacuating said chamber to lower the pressure therein substantially below atmospheric pressure, and detonating said explosive charge to apply substantially uniform force radially outwardly in an amount sufficient to deform said tubular blank into said bulbous shape.

3. A method of forming a bulbous article from an elongate hollow tubular blank having a mid-portion of larger diameter than each of the two end portions adjoining said mid-portion, said method comprising:

supporting said blank in a surrounding die having a hollow cavity therein, placing an explosive charge within said blank, filling said blank with shock-wave transmitting material,

placing said die into a vacuum chamber, evacuating said chamber to lower the pressure within said die cavity substantially below atmospheric pressure, and

detonating said explosive charge to apply substantially uniform force radially outwardly in an amount sufficient to deform said tubular blank into said bulbous shape.

4. A method of forming a bulbous article by explosive force applied to a hollow workpiece, said method comprising:

placing said workpiece in a surrounding die having a cavity therein, placing said die within a surrounding vacuum chamber, placing an explosive charge in spaced relationship from said workpiece, evacuating said vacuum chamber to lower the pressure in said die cavity substantially below atmospheric pressure, and

detonating said explosive charge to apply force to said workpiece and deform the same.

5. A method of forming an article from an elongate hollow tubular blank comprising the steps of:

placing said tubular blank in a surrounding die having 5
a workface spaced apart from said workpiece,
placing said die in a vacuum chamber,
placing an explosive charge within said blank,
filling said blank with shock-wave transmitting material,
evacuating said chamber to lower the pressure in said 10
die substantially below atmospheric pressure, and
detonating said explosive charge with sufficient force
to deform said blank into contact with said work-
face.

6. A method of forming a bulbous article from an 15
elongate hollow tubular blank having a substantially constant initial cross-sectional area along some portion of its length, said method comprising:

placing an explosive material circumferentially sym-
metrical about the outer surface of said blank at 20
two spaced-apart locations along said portion,
detonating said explosive material to apply substan-
tially unifrom circumferential force to said blank in
a radially inward direction to reduce said initial
cross-sectional area at each of said locations,
placing an explosive charge within said blank at a 25
location intermediate said spaced-apart locations, and
detonating said explosive charge to apply force to said
blank radially outwardly in an amount sufficient to
deform the material therein.

7. The method set forth in claim 6 above, further including:

prior to said final detonating step, placing said blank 30
in a vacuum chamber, and
evacuating said chamber to lower the pressure therein 35
substantially below atmospheric pressure.

8. The method set forth in claim 6 above, further in-
cluding:

prior to said final detonating step, placing said blank in 40
a die having a cavity therein, and
filling said blank with shock wave transmitting material.

9. A method of forming a bulbous article from an 45
elongate substantially cylindrical rigid blank, said method comprising:

placing rigid but crushable filler material within said
blank,

placing a protective sleeve of flexible force-transmitting
material circumferentially around said blank at a
first axial location thereon,

placing an explosive material circumferentially sym-
metrical around said protective sleeve and substan-
tially aligned axially therewith,

detonating said explosive material to apply substantially
uniform circumferential force to said blank in a
radially inward direction to decrease the cross-sec-
tional size of said blank and increase the wall thick-
ness of said blank at said location,

repeating all the above steps at a second axial location
on said blank, said second location being spaced apart
from said first location,

placing said blank in a die having a hollow cavity and
adapted to support said blank at said first and second
locations and to leave the portion of said blank be-
tween said spaced apart first and second locations
unsupported within said hollow cavity,

filling said blank with shock wave transmitting material,
placing an explosive charge within said blank,
placing said die within a vacuum chamber,

evacuating said chamber to lower the pressure in said
die cavity substantially below atmospheric pressure,
and

detonating said explosive charge to deform said blank
outwardly in said unsupported portion.

10. In apparatus for explosively forming an article by
deformation of a fluid-containing workpiece:

die means including a die for surrounding said work-
piece,

platform means for supporting said die,

vacuum chamber means comprising an enclosure for
containing said die to isolate said die from sur-
rounding atmosphere, said enclosure being supported
on said platform means, and

seal means for sealing said vacuum chamber means to
said platform means in pressure-tight relationship.

11. The apparatus set forth in claim 10 above, wherein:
said enclosure comprises a substantially cylindrically
shaped chamber having an annular flange thereon,
and

said seal means comprises an annular groove in said
platform means and a flexible ring contained within
said groove and adapted to be substantially uniform-
ly compressed within said groove by said flange.

12. A method of forming a throat section in a rigid
elongate cylindrical blank having a substantially constant
initial cross-sectional area along some portion of its
length, said method comprising:

placing an explosive material circumferentially sym-
metrical about the outer surface of said blank at a
location along said portion, and

detonating said explosive material to apply substan-
tially uniform circumferentially distributed radially
inwardly directed force to said blank to reduce the
cross-sectional area thereof to a minimum at said
location whereby said initial cross-sectional area
progressively decreases on either side of said loca-
tion toward said minimum cross-sectional area,

initially preplacing firmly rigid but crushable filler ma-
terial within said blank prior to said detonating step,
placing a protective sleeve of flexible force-transmitting
material circumferentially around said blank and in
contact with the outer surface thereof prior to place-
ment of said explosive material, and
arranging said explosive material in substantial align-
ment axially over said sleeve, and
restraining both ends of said elongate cylindrical blank
to prevent movement of said ends during said detonat-
ing step.
